UNITED STATES PATENT OFFICE

FRIEDRICH KARL SCHMIDT, OF SPELDORF, MUELHEIM-ON-THE-RUHR, GERMANY

APPARATUS FOR PREVENTING THE PASSING OF DANGER SIGNALS

Application filed September 18, 1929, Serial No. 393,457, and in Germany December 3, 1927.

Apparatus is known for automatically operating a signal or brake on a moving train in order to prevent the passing of danger signals.

5 This invention relates to apparatus of the kind in which section stops dependent on the position of the signals are acted upon by stops on the train which in their turn then operate a source of power such as a spring or 10 the like which actuates the signal or brake mechanism.

For the greater part apparatus that has hitherto been made has the disadvantage that the signalling or brake apparatus act accidentally when the stops on the train come into contact with obstacles on sections of the line. Furthermore most of the apparatus of this kind are unreliable in their action and are impracticable because the rocking levers used 20 as the stops on the trains are not capable of withstanding the stresses imposed which are of the character of a blow when the velocity of the train is high and often lead to breakage.

25 The invention has among its objects to provide by the combination of a number of features an apparatus which will act with certainty in both respects, that is to say, which on the one hand is independent of all 30 obstacles no matter of what kind, and which on the other hand will not be damaged by the heavy blows to which they may be subjected when the train is travelling at a high velocity.

35 The invention comprises the combination of a number of vehicle stops, which are provided as elastic bars, tightly held in position and made mutually dependent by intermediate locking members, with section stops 40 which are so arranged with respect to the vehicle stops that the locking members are released in a certain sequence by the deflection of the vehicle stops, and in order that the actuating means of the signalling or 45 brake apparatus e. g. springs or the like may be released at certain intervals in sequence.

This ensures that accidents occasioned by obstacles on the sections of the line are avoided and that thus all accidental actuation of the apparatus is prevented with cer-

tainty. Experiments have shown that the apparatus passes over widely spaced sleepers without being actuated or damaged even at high speeds.

It is obviously possible to vary, to group, 55 and to stagger the section stops which determine the sequence of operation.

In order further to increase safety it is proposed according to the invention that each 60 elastic stop bar be connected by a system of locking levers to the next bar, which is in each case only released when the preceding bar in the sequence is flexed.

In this way the sequence is preserved in a 65 particularly simple manner and it is rendered certain that the desired effects happen only after the release of a series of particular locking members.

The construction of the apparatus may be 70 varied without departing from the invention. Thus it is possible with known structural means so to arrange the section stops into groups that after the operation say of the first group consisting of three stop bars, in a definite sequence, the operation of a fourth 75 group may cause an acoustic or optical signal to be operated, while on the operation of further bars one of them operates the ordinary brake and after releasing the last of them this operates the quick acting brake. 80 To adapt it to the methods of working distant and danger signals the arrangement may also be so provided that on passing a distant signal set at danger, a warning signal which only responds to a definite part of the 85 sequence will be operated, while on passing the main signal the quick acting brake acts at once in the last part of the sequence.

One construction according to the invention 90 is shown diagrammatically in the accompanying drawing, in which

Figure 1 is a front general elevation.

Figure 2 is a plan of the vehicle stops and mounting on the axle.

Figure 3 shows on an enlarged scale a system of locking levers for a vehicle stop which will act in both running directions.

Figure 4 is a section in plan on the line 95 a—a of Figure 3.

Figures 5 and 6 are views similar to Fig- 100

ures 3 and 4 in which the position is indicated in which the vehicle stop is deflected.

Figure 7 shows the apparatus in the position after a bar has come into contact with 5 a section stop.

Figure 8 is a plan view, to a smaller scale, of the section stops.

Figure 9 is a view similar to Figure 7, showing 10 means operated by the last vehicle stop for controlling the action of a signal device or the brakes.

Figure 10 is a plan view of the mechanism shown in Figure 9.

In the accompanying drawings 1 are the 15 two rails of the track. Between the rails are provided section stops 2, 3, 4 and 5 which are operated by a signal wire from the operating mechanism, and which can either be raised and lowered or held erect and 20 turned down, whereby they either are brought into the path of the stops on the vehicle or assume such a position that the vehicle stops pass over them without acting upon them. The operation of these section stops may 25 conveniently take place in dependence upon the operation of the main and distant signals, the particular signal wires being positively connected to each other.

The section stops 2, 3, 4 and 5, as illustrated in Figure 8, are staggered in relation to each other in the direction in which the train runs, e. g. in such a way that stop 2 is farthest in front in the direction of the approaching train, after which the stop 3 30 for example follows somewhat further back, while stop 4 is again arranged a little way behind and finally stop 5 is again set a little farther back in staggered order. Any other variation and relative position of the stops 40 is obviously possible in the plane running at right angles to the track, so as to obtain any desired sequence in the actuation of the vehicle stops.

With the section stops 2, 3, 4 and 5 vehicle stops in the form of elastic bars 6, 7, 8 and 45 9 coact. These bars are in each case rigidly clamped at 10 in a bearing flange 12. The bearing flanges 12 are mounted stationary on an axle of the vehicle which may conveniently be the last axle 11 on the tender. The bearings 12 are prevented from rotating by pinlike projections 12^x engaging with a sufficient amount of play in guides 12^{xx} connected to the resilient part of the vehicle, so that 50 the apparatus mounted on the unsprung part of the vehicle will not be acted on when the flexure takes place. To one arm of the bearing flange 12 is affixed a box-like casing 6^x in which is arranged, in the direction of the 55 track, and opposite to, that is, always in front and behind each of the bars 6, 7 and 8, a bell crank lever 13, 14 and 15, respectively. The downwardly directed arms of these bell crank levers communicate by a roller 60 mounted at the end, with the bars 6, 7 and

8 in such a way that when each bar is flexed by striking the corresponding section stop, it is rocked about its bearing pin 15^x. When this takes place the upper substantially horizontal arms of the bell crank levers 13, 14 70 and 15 act like cams on the locking levers 17, 18 and 19 (Figures 1, 5 and 6) which are rotatable about a centre pin in a plane at right angles to the direction in which the train is running. The bell crank levers are 75 so arranged that they may always act only on the left hand end of each locking lever when the train is running forwards and on the right hand end of the locking lever when it is running backwards. It must be noted 80 however that in the constructional example illustrated the arrangement is such that the apparatus is effective without changes both for forward and backward running. For this purpose the bell crank levers and other locking devices are provided in each case on both sides of each stop bar as shown in Figures 85 3 to 6. When it is necessary, a simplified construction may be utilized in which one pair of the levers 13 and 14 and rocking lever 20 for each bar is dispensed with, so that it will then only operate for forward running.

Above the bell crank levers 14 and 15 at bars 7 and 8 and likewise in the same plane at bar 9, are provided rocking levers 20 rotating on pins 20^x. These rocking levers as shown in Figures 4 to 6 are provided with a lateral recess 21 and a nose 22. Against these latter bear the locking levers 17, 18, 19 when they are in the horizontal position and thereby 95 prevent the lateral movement of the rocking levers 20. If however the corresponding end of the locking lever be lowered, the nose 22 can engage over the locking lever and swing it outwards. The adjacent locking lever is 100 under the control of the horizontal arm of the bell crank lever of the preceding bar and is not affected by the movement of the said rocking lever 20, owing to the recess 21, (see Figures 4 and 6).

When the locking levers 17, 18 and 19 are 110 horizontally disposed, the rocking levers 20 prevent the flexure of the bars, and thereby also the release of the actual signalling or brake members, as in this position the rocking levers strike against the right hand end of the locking levers 17, 18, 19 when the train runs forwards and against the left hand end of the locking levers 17', 18', 19' when it runs backwards. When, however, the locking levers are in the inclined position determined 115 by the action of the bell crank levers which engage them they release the rocking levers 20 and the apparatus can now be operated in sequence because the rocking levers can be swung over, as the nose 22 passes above the adjacent locking lever, and then each bar 7, 8, 9 can be flexed at the point 10 where it is clamped.

Supposing for example as shown in Fig- 120

ures 5 to 7, the bar 6 strikes against the corresponding section stop 2, the bar bends to the form shown in Figure 7. It thereby presses the lower arm of the bell crank lever 13, to one side and the upper horizontal arm of this bell crank lever lifts the corresponding locking lever 17 on the left and depresses it to the right, so that it is brought into the position shown by dotted lines in Figure 1. 5 In this way the rocking lever 20 of the succeeding bar 7 will be released, so that it can swing outwards about the pivot pin 20'. This takes place when the bar 7 strikes against the section stop 3 and in its turn is bent as shown 10 in Figure 7, by the release of the rocking lever 20 which has now become possible. By the prescribed flexure the bar 7 pushes the corresponding rocking lever 20 over the depressed right hand end of the locking lever 17 and at the same time by the bell crank lever 14 lifts the left hand end of the locking lever 18, so that this latter assumes the same inclined position as the locking lever 17 held before. In this way the path for the 15 bar 8 and for the other corresponding rocking lever is opened. When the bar 8 strikes against the stop 4 it is bent and by this means the rocking lever 20 again moves over the right hand end of the locking lever 18, the bell crank lever 15 being simultaneously so affected that it raises the locking lever 19 on the left and depresses said lever on the right. The lever 20 can now swing over the depressed right hand end of the locking lever 20 20 and release the bar 9. This bar bends when it strikes against the stop 5. By the proper outward swing of the last bar 9 a spring (not shown), or other source of power is acted on and in its turn operates either a 25 signalling device or the brakes of the train. This may be effected by any suitable means. Thus, as shown in Figures 9 and 10, the vehicle stop 9, when deflected, may serve to press inwardly a plunger valve 28 against the 30 action of a spring 27 into a containing casing 29. The plunger valve 28 represents a controlling member in a pipe 30 for compressed air or steam, which pipe leads to the signalling or braking device. The inward movement of the plunger brings the hole 31 into a 35 position where the operating medium may flow freely through the pipe 30 and causes the signal or brake to act. The various levers are so constructed that they return automatically and by their own weight after they 40 have moved to the position shown in Figure 3. It is also possible to provide special springs on each of the levers for this purpose. 45

60 I claim:—

1. Apparatus for preventing the passing of danger signals by the operation by automatic control of a source of power effecting the actuation of a signalling or brake mechanism, the said control being effected by means 65

of stops on the train operated by stops on the track, comprising a series of elastic rigidly mounted vehicle stops upon the train, co-operating track section stops staggered relatively one to the other to engage the vehicle stops in sequence, and locking mechanism provided for each vehicle stop except the first to render the said vehicle stops dependent upon the actuation of the preceding stop, the last of said vehicle stops serving to effect the control of the source of power. 70

2. Apparatus according to claim 1, provided with locking mechanism comprising locking levers extending between each pair of vehicle stops and intermediate elements in the form of rocking levers for all the vehicle stops except the first, which rocking levers are locked to prevent deflection of the corresponding vehicle stops until released by the corresponding locking lever. 75

3. Apparatus according to claim 1, provided with locking mechanism comprising locking levers extending between each pair of vehicle stops, intermediate elements in the form of rocking levers for all the vehicle stops except the first, which rocking levers are locked to prevent deflection of the corresponding vehicle stops until released by the corresponding locking lever, and bell crank levers applied to all the vehicle stops except the last, said bell crank levers being caused upon deflection of the corresponding vehicle stop to act upon the corresponding locking lever to release the succeeding vehicle stop. 80
